(57) **CLAIM**

The ornamental design for a seat cushion for a moveable seat bottom, as shown and described.

DESCRIPTION

FIG. 1 illustrates a top, front perspective view of a seat cushion for a moveable seat bottom of a passenger seat, showing our new design, and showing appearance in one mode of use on a passenger seat (shown in broken lines); FIG. 2 illustrates a top, front left perspective view of a seat cushion for a moveable seat bottom of a passenger seat, showing our new design; FIG. 3 illustrates a bottom, rear right perspective view of the seat cushion of FIG. 2; FIG. 4 illustrates a left side elevation view of the seat cushion of FIG. 2; FIG. 5 illustrates a right side elevation view of the seat cushion of FIG. 2; FIG. 6 illustrates a front side elevation view of the seat cushion of FIG. 2; FIG. 7 illustrates a rear side elevation view of the seat cushion of FIG. 2; FIG. 8 illustrates a top plan view of the seat cushion of FIG. 2; FIG. 9 illustrates a bottom view of the seat cushion of FIG. 2; FIG. 10 illustrates a left side elevation view of a seat cushion for a moveable seat bottom of a passenger seat, showing our new design, and showing appearance in one mode of use with a user (shown in broken lines) generally sitting on a main portion of a top portion of the seat cushion of the passenger seat (shown in broken lines), and with the seat bottom in a stowed, generally horizontal position; and, FIG. 11 illustrates a left side elevation view of a seat cushion for a moveable seat bottom of a passenger seat, showing our new design, and showing appearance in one mode of use with a passenger (shown in broken lines) sitting on a top portion of the seat cushion of the passenger seat (shown in broken lines) with the passenger's bottom generally resting on a generally horizontal secondary portion of the top portion of the seat cushion of the passenger seat (shown in broken lines).

(Continued)

portion of the deployed seat cushion, and with the seat bottom in a deployed, inclined position.

The broken lines in the drawings depict the user and portions of the passenger seat that form no part of the claimed design.
